UNITED STATES PATENT OFFICE

142,203

DESIGN FOR A FACEPIECE FOR GAS MASKS OR RESPIRATORS

William H. Lehmburg, Newton Center, Mass., assignor to Beckwith Manufacturing Company, Dover, N. H., a corporation of New Hampshire

Application March 18, 1942, Serial No. 106,230

Term of patent 14 years

(CL. D63—1)

To all whom it may concern:

Be it known that I, William H. Lehmburg, a citizen of the United States, residing at Newton Center, in the county of Middlesex and Commonwealth of Massachusetts, have invented a new, original, and ornamental Design for a Facepiece for Gas Masks or Respirators, of which the following is a specification, reference being had to the accompanying drawing, forming a part thereof, in which

Figure 1 is a view in perspective of a facepiece for gas masks or respirators embodying my new design,

Fig. 2 is a cross-sectional view on the line II—II of Fig. 1.

I claim:

The ornamental design for a facepiece for gas masks or respirators, substantially as shown.

WILLIAM H. LEHMBURG.
